GAS BURNER

Filed Feb. 15, 1929

UNITED STATES PATENT OFFICE

GILBERT E. SEIL, OF CONSHOHOCKEN, PENNSYLVANIA

GAS BURNER

Application filed February 15, 1929. Serial No. 340,037.

My invention relates to gas burners, but more particularly and primarily to burners wherein the air for supporting combustion is delivered at high temperatures; for example, temperatures ranging from 2000° Fahrenheit upwards. Although the burner has been designed primarily for use when the air for supporting combustion is supplied at high temperatures as suggested it is to be understood that devices embodying the invention are not limited to use with air at such high temperatures but the same are well adapted for use when air at lower temperatures (even ordinary room temperature) is employed.

The burner is particularly adapted for use in the heating of furnaces wherein bricks or other articles of refractory material are "burnt". As they are removed from the furnace they pass through a flume or conduit through which air for cooling the same is caused to flow. The said flume leads to the rear side of the burner and the air is drawn therefrom and therethrough by the suction action of the gas as it is discharged from the burner, as hereinafter will be set forth. In other words, the construction of the burner is such that the discharge of combustible gas therefrom operates to create a suction upon the air and cause its flow through the flume to and through the burner concentrically with the gas to effect thorough intermingling thereof with the combustible gas, whatever its character, which is delivered from the burner.

The general object of the invention is to provide a burner of simple but novel construction of a character such that the discharge of the combustible gas therefrom operates to create a suction effect whereby air is drawn thereto and therethrough to supply the oxygen necessary for effecting combustion of the gas.

It also is an object of the invention to provide a burner of novel construction including means whereby the flow of combustible gas therefrom operates to induce a flow of air through the burner whereby intermingling thereof with the gas is effected.

A further object of the invention is to

provide a structure of novel character having means whereby a primary and a secondary induction of air and the intermingling thereof with the fuel are effected by the flow of fuel from a burner constituting a part of the structure.

Another object of the invention is to provide a structure of novel character including means whereby the amount of air induced by the flow of combustible gas from the burner and caused to intermingle with the said gas may be regulated and controlled as required for efficient combustion.

A still further object of the invention is to provide a gas burner, from which a combustible gas is adapted to be discharged at high velocity, having means whereby the discharge of such gas from the burner induces a high velocity current of air in the same direction, the streams of gas and air uniting with great turbulence whereby complete and thorough intermixing thereof is effected.

I have not undertaken to point out here all of the various objects and advantages which are incident to my invention but other and further objects thereof will be specifically set forth in the detailed description thereof which follows or will be apparent from such description.

In order that the invention may be readily understood and its manifold practical advantages fully appreciated reference should be had to the accompanying drawings wherein I have illustrated one mechanical embodiment thereof in the form which is at present preferred by me.

In the drawings:

Fig. 1 is a view in central longitudinal section of a structure including a gas burner, embodying the invention, taken on the line 1—1 of Fig. 2;

Fig. 2 is a view partly in elevation and partly in section of the burner looking from the left toward the right in Fig. 1 of the drawings;

Fig. 3 is a view in inside elevation of the rear section or part of the burner; and

Fig. 4 is a section taken on the line 4—4 of Fig. 2.

In the drawings I have shown a burner

comprising relatively flat sections or parts 1 and 2 which are adapted to be secured and held together by means of bolts 3 which extend through openings provided in the parts 5 1 and 2 in adjoining relation to their outer edges. The rear section or part 1 is provided upon its inner side with an annular depression or hollowed-out portion 4 which is surrounded by a shoulder 5. The section 10 1 is provided with a centrally located tapered opening 6 the inner end of which terminates in a forwardly extending cylindrical portion 7. The wall 8 which surrounds or forms the centrally located tapered opening 15 6 extends inwardly beyond the plane of the rear or inner side of the part or member 1. The said wall is tapered and inclined forwardly as indicated in Fig. 1 of the drawings. The section or part 1 is provided with 20 an annular chamber 10 surrounding the rear or outer portion of the tapered wall 8. The other section 2 is provided upon the outer edge portion of its inner side with an annular groove or notch which provides a shoulder 25 11 which is adapted to contact with and fit tightly against the annular shoulder 5 of the section or part 1. Preferably the fit should be so close as to require force to effect engagement of the shoulders 11 and 5 in the 30 manner as shown in Fig. 1 of the drawings. Such a fit is necessary to prevent the escape of gas as hereinafter will be apparent and obvious. The central portion of the inner or rear side of the section or part 2 is also 35 hollowed out as indicated at 12, such hollowed out portion being in opposed relation to the hollowed out portion 4 of the member 1 so as to provide an annular chamber to receive gas from the gas supply pipe 15. 40 The section or part 2 is provided with a centrally located opening 16 into which the cylindrical projecting portion 7 located at the front end of the wall 8 projects. The section or part 2 is provided with an annular 45 chamber 18. Partition walls 20 and 21 extend across the respective annular chambers 10 and 18 provided in the two sections or parts 1 and 2 previously referred to herein. The inner wall of the section or part 1 is provided 50 with an opening 22 which is located near the outer edge thereof while the inner wall of the section or part 2 is provided with a similar opening 23 which in the construction shown is located in opposed relation to 55 the said opening 22. Both of these openings 22 and 23 flare outwardly as indicated so that the surfaces thereof cooperate to form an annular groove which is angular in cross section as indicated. Within this groove is 60 placed an annular bushing 24.

For the purpose of supplying water or other cooling fluid to the annular chambers 10 and 18 a pipe 25 is employed from which the cooling fluid is first delivered into the 65 chamber 10 at a point in adjoining relation

to the partition wall 20. The fluid so delivered travels through the said chamber to a point in adjoining relation to the opposite side of the said partition wall and then flows through the opening of the bushing 24 into the chamber 18 in adjoining relation to one side of the partition wall 21 and thence through the said chamber to a point in adjoining relation to the opposite side of the said partition wall 21 and thence outwardly 70 through a pipe 26 through which the fluid may be either returned to the source or conducted away to some other point and discharged. 75

In the construction as illustrated the pipe 25 through which the cooling fluid is supplied to the burner is shown as surrounding and in concentric relation to the gas supply pipe 15. The flow of the cooling fluid therethrough operates to prevent the gas from becoming overheated. The cooling of the burner and of the gas supply pipe in the neighborhood of the burner is necessary if the air supplied to and which surrounds the burner is at a high temperature, as usually 80 will be the case when the burner is employed for the heating of furnaces used in the industrial arts; but if the air is employed at a lower temperature, for example, at room temperature, cooling thereof is not necessary 85 and no means for that purpose need be provided. 90

The gas for the burner is supplied under pressure to the annular chamber provided by the hollowed out annular portions 4 and 100 12, previously referred to, and is discharged therefrom at relatively high velocity through the narrow annular orifice 30 between the forwardly projecting portion 7 and the adjoining portion of the wall of the opening 16 of the member 2. The velocity at which the gas is discharged from the burner depends upon the pressure of the gas and also is affected by the width of the slit forming the orifice 30. The pressure of the gas within the annular chamber of the burner may vary through a wide range. It has been found that when producer gas is employed a pressure of one pound per square inch is sufficient to cause the discharge of the same 105 from the orifice 30 at a velocity high enough to induce a flow of air through the center of the burner in quantity sufficient to supply the oxygen requisite for complete combustion. Of course it will be understood that 110 the width of the slit forming the orifice 30 should be sufficiently narrow to provide the required velocity of the gas upon its discharge. In other cases the pressure should be greater. Pressures as high as twelve 115 pounds per square inch have been employed and higher pressures than that may be employed if found to be desirable or necessary. The purpose is to cause discharge of the 120 gas from the burner at a velocity sufficiently 125 130

high to induce such a flow of air as will provide an amount requisite to effect complete combustion of the gas.

It will be understood that when gas is discharged from the orifice 30 at what may be regarded as a high velocity a partial vacuum or decrease in air pressure is created in advance of the front or inner end of the cylindrical projection 7 which causes the air to flow with corresponding velocity through the burner, such velocity depending upon the velocity at which the gas is discharged from the orifice 30. The creation of a partial vacuum or decrease in pressure in front of the orifice 30 tends to cause an inward or contracting movement of the gas, the partial vacuum space or space of decreased pressure within the annular stream of gas being of practically cone-shape. The air, rushing in from the rear through the central opening 6, collides with the gas so that the latter is broken up with considerable—even with great—turbulence, and a thorough intermingling of the gas and air thereby effected.

For the purpose of aiding in separating the parts 1 and 2 from each other I have provided upon the said parts projections 31 which extend radially from their outer edges or peripheries.

Generally the burner constructed and operated as hereinbefore described, which may be referred to as a primary induction means, will supply all of the air requisite to effect complete combustion of the gas, but there may be times when it will become desirable to provide a secondary induction means for supplying an additional quantity of air. In the construction as illustrated such secondary induction means comprises a block 32 of refractory material in front of the burner, which block is provided with a Venturi opening 33 in alinement with the central opening through the burner. The diameter of the Venturi opening 33 at its most narrow part preferably is greater than the diameter of the opening 16 through the section or part 2 of the burner. The discharge of the gas and the air into the Venturi opening 33 effects an induction of air through the space between the front side of the burner and the rear side of the said block 32. By adjusting the burner toward and from the block to vary the width of the space between the adjoining side of the burner and the block the amount of air induced by the secondary induction may be varied, and thus the quantity of air which is combined with the gas regulated and controlled.

The quantity of air or other gas containing oxygen discharged through the central opening of the burner in concentric relation with the annular stream of gas discharged from the orifice 30 may be regulated by reducing the size of the tapered opening 6

and of the opening through the cylindrical part 7 which projects forwardly from the inner or forward end of the tapered portion 8. The size or diameter of the said opening may be varied by placing therein a lining 34 such as is shown in Fig. 4 of the drawings. The said lining is mounted removably in the said opening so that linings of different thicknesses may be employed to thereby vary, as may be desired, the size of the opening through which the air passes. The amount of air may be further varied and controlled by adjusting the lining toward and from the opening through the burner. The lining also serves as a means for protecting or insulating the metal parts of the burner from the heat of the hot air which may surround and be discharged through the burner.

I have referred heretofore to the fact that the discharge of the gas from the circular orifice 30 at high velocity as described creates a partial vacuum, in adjoining relation to the said orifice, which is cone-shaped. The apex of the said cone-shaped vacuum space usually is located at a point in the Venturi opening or passageway 33 in the region of the portion of smallest diameter thereof.

It has been found by actual experience that the air is drawn by induction through the central opening in the burner at high velocity. It will be apparent that upon the entry of the air into the cone-shaped vacuum space, produced interiorly of the stream of gas in adjoining relation to its point of origin, it not only expands but moves forward in the same direction as that of the stream of gas, and in expanding results in such turbulence as to effect complete intermingling of the gas and air. Such thorough intermingling of the air, or other gas containing oxygen, with the combustible gas conduces to and brings about complete combustion whereby the efficiency of the burner in the production of high temperatures is enhanced to a substantial degree.

By the employment of a burner of the construction and operating according to the principle disclosed the quantity of air necessary to supply oxygen in a quantity sufficient to combine with the combustible gas to effect complete combustion thereof is supplied without the aid or use of pumps or other mechanical means. That not only is a circumstance and factor increasing the economy of operation but it is a factor of great importance when the air which is supplied to the burner is of high temperature, as heretofore mentioned. In the handling of air at such temperatures it might be difficult to provide pumps or other mechanical means for that purpose,—at any rate, it would be necessary to provide cooling means for such pumps or other mechanical means and the provision of such cooling means

would involve greater or less expense and the operation thereof would involve a continuing expense. Therefore it will be apparent that by my invention I have provided a burner which not only operates with great efficiency in the combustion of gases but by its use various expenses heretofore necessary to be incurred may be avoided.

A construction such as that above described 10 embodying the invention is of especial advantage in cases where the gas and air pressures in front of the burner are or may be greater than the pressures on the opposite side thereof. Under such conditions the 15 products of combustion would tend to flow back or in the reverse direction into and through the air opening of the burner. In the construction embodying my invention the air is drawn forward by the suction 20 action of the stream of gas as it is discharged from the burner with such force and with a velocity sufficient to prevent a back flow of the gaseous products of combustion.

Having thus described my invention, what 25 I claim and desire to secure by Letters Patent is:

A device of the character described, comprising a gas burner comprising two sections and having means for securing said 30 sections together, the said sections having annular hollowed out portions upon their inner sides which cooperate to form an annular chamber adapted to hold gas under pressure, each of the said sections having 35 central openings which extend therethrough, one of the said openings being tapered and terminating in a projection which extends into the inner end of the opening of the other section and being spaced therefrom to provide 40 an orifice through which gas is adapted to be discharged from the said annular chamber, and the said burner also comprising chambers therein which are adapted to receive and through which a cooling fluid is 45 adapted to pass, a pipe for supplying gas to the first named chamber, and a pipe for supplying a cooling fluid to the second named chambers, the said last mentioned pipe surrounding and being concentric with the pipe 50 for supplying gas to the said first named chamber.

In testimony that I claim the foregoing as my invention I have hereunto signed my name this 12th day of February, 1929.

55 GILBERT E. SEIL.
